UNITED STATES PATENT OFFICE.

ALFRED E. MASKREY, OF CANTON, OHIO, ASSIGNOR, BY MESNE ASSIGNMENTS, OF
ONE-HALF TO KENNETH UMSTEAD, OF SALEM, OHIO.

METAL BAND.

1,389,208.

Specification of Letters Patent. Patented Aug. 30, 1921.

Application filed November 28, 1913, Serial No. 803,519. Renewed January 29, 1921. Serial No. 441,073.

To all whom it may concern:

Be it known that I, ALFRED E. MASKREY, a subject of the King of Great Britain, residing at Canton, in the county of Stark 5 and State of Ohio, have invented certain new and useful Improvements in Metal Bands, of which the following is a specification.

The invention relates to metal bands of 10 the kind employed for marking fowls and other animals, as for instance for encircling the leg of a chicken for carrying a number or other marking thereon; and the object of the improvement is to provide a band of 15 this character which can be readily applied and adjusted to chicken legs of different sizes, and when so applied and adjusted will be retained on the leg without inconvenient or injurious results.

20 The objects of the improvement, thus briefly mentioned, are attained by making the band of pliable sheet metal with a series of spaced recesses pressed or indented along one end portion, and a corresponding 25 protrusion formed or indented on the other end portion for engaging one of the recesses, with lateral tongues on the same end portion for clamping the end portions together on each side of the protrusion when engaged in one of the recesses.

A preferred embodiment of the invention thus set forth in general terms is illustrated in the accompanying drawing, forming part hereof, in which—

35 Figure 1 is a perspective view of the band showing its end portions secured together as in use;

Fig. 2, a plan view of the metal strip as formed and shaped for making the band;

40 Fig. 3, an edge view of the same;

Fig. 4, an annular section of the band as shown in Fig. 1;

Fig. 5, a cross section of the band as on line 5—5, Fig. 1; and

45 Fig. 6, a plan view of a modified form of a metal strip showing the recesses cut in one end portion thereof.

Similar numerals refer to similar parts throughout the drawing.

50 The metal strip 1 or 1^a may be made of aluminum or other pliable metal and when used for encircling the leg of a chicken the band may be made of twenty-six gage metal about three inches in length and one-half inch or 55 less in width.

The series of spaced recesses 2 or 2^a are pressed or indented along the middle of one end portion of the strip, and these recesses may be in the form of the stamped indentations 2 having blunt or rounded outer surfaces, as shown in Figs. 1 to 5 of the drawing; or may be in the form of the cut out perforations 2^a, as shown in Fig. 6 of drawing.

The protrusion 3 is formed on the other 60 end portion of the metal strip, which protrusion may be conveniently made by stamping or indenting it from the body of the metal, as shown in the several figures, and is arranged to enter and engage one of the 65 recesses in the other end when the recess is applied over and around the protrusion.

Two pairs of lateral tongues 4 are provided on the end portion of the metal strip which carries the protrusion 3, and these 70 tongues are so spaced apart that the protrusion occupies an intermediate position between them; and it is evident that when the other end portion of the metal strip is bent to form a circular band, one of the 75 recesses 2 or 2^a therein may be engaged with the protrusion 3, and the lateral tongues may be bent and clamped around the overlapping end portion on both sides of the 80 engaging protrusion; by which means the 85 end portions are securely held together.

It is evident that the metal band thus made and applied is free from an excessive number of folds and is limited to a single 90 thickness of metal, excepting the double thickness where the end portions over-lap, and the triple thickness where the tongues clamp the over-lapped parts together. Furthermore, there are no notches or recesses 95 opening against the leg of the chicken in which to catch and retain dirt; nor any internal or external protrusions to injure the leg or catch external objects. And finally, the series of recesses provide means for a corresponding series of adjustments to form 100 a band suitable for legs of different sizes; and such recesses together with the tongues provide means for readily and firmly securing the ends of the band together without the aid of separate locking bands or 105 the like.

The end portions of the strip 1 or 1^a of which the band is made, are preferably cut somewhat narrower than the intervening middle portion thereof, so that when 110

the tongues 4 are folded to clamp around the overlapping end portion, the bends of the tongues will not protrude beyond the wider middle portion of the band strip.

5 I claim:

1. A band formed from a strip of pliable sheet metal having a series of spaced recesses in one end portion and a protrusion on the other end portion, and lateral tongues on one of the end portions adapted to be clamped around the other end portion to hold the protrusion in engagement with one of the recesses when the end portions are overlapped.
- 15 2. A band made of pliable sheet metal with a series of spaced recesses along one end portion, a pair of spaced lateral tongues on each side of the other end portion, and a protrusion on the same end portion in alignment with the spaces intermediate the tongues, whereby the end portions may be overlapped, the protrusion engaged with one of the recesses, and the tongues clamped upon the overlapping end portion.
- 20

3. A band formed from a strip of pliable sheet metal having a series of spaced recesses in one end portion and a protrusion on the other end portion, and lateral tongues on one of the end portions adapted to be clamped around the other end portion to hold the protrusion in engagement with one of the recesses when the end portions are overlapped, the end portions of the strip being narrower than the middle portion thereof, so that the clamped tongues will not protrude beyond the adjacent edges of the band.

4. A labeling band having in combination interengaging means on its opposite ends, and means formed integrally with one end of the band for holding the other end of the band lapped thereupon with the interengaging means in engagement with each other.

ALFRED E. MASKREY.
